UNITED STATES PATENT OFFICE.

ARTHUR W. LE BOEUF, OF WOONSOCKET, RHODE ISLAND, ASSIGNOR TO ELECTRIC
COMPOSITOR COMPANY, OF NEW YORK, N. Y., A CORPORATION OF NEW JERSEY.

LINOTYPE-MOLD.

1,027,551.

Specification of Letters Patent. Patented May 28, 1912.

Application filed April 23, 1909. Serial No. 491,831.

To all whom it may concern:

Be it known that I, ARTHUR W. LE BOEUF, a citizen of the United States, residing at Woonsocket, in the county of Providence and State of Rhode Island, have invented 5 a certain new and useful Improvement in Linotype-Molds, of which the following is a full, clear, and exact description.

In linotype machines, the molds move between the position in which the molten type metal is injected from a nozzle into the type slot, and the position in which the linotype is ejected from said mold slot. It is the usual practice to place a trimming knife in such position that as the mold moves from the former to the latter position, this knife will contact with the back face of the mold, spanning the slot, and will, therefore, trim the bottom of the linotype in said slot. 10 The metal in the mold slot contracts a little as it cools, and therefore the linotype can be moved rather easily in said slot; and, in fact, does freely move during this trimming operation if it is not anchored in said slot. 15 If it does move, even a very little, the bottom of the linotype will not be trimmed in exact parallelism with the printing surface, and therefore the linotype will be higher in some places than in others, and will be imperfect. 20

This invention relates particularly to providing a mold with efficient means for anchoring the linotype in the slot while the mold is moving from the casting to the ejecting position, so that the bottom of the linotype may be trimmed in perfect parallelism with the printing surface thereof, and for withdrawing said anchorage when the ejecting position has been reached. 25

The principal part of the invention consists in combining with the mold two or more movable pins which may be caused to project slightly into the mold slot, while the metal is being ejected and while the mold is being moved from the casting to the ejecting position, and for causing the withdrawal of said pins when the ejecting position is reached, so that the linotype may be easily ejected from the slot. 40

In the drawing, Figure 1 is a bottom view of a linotype mold—that is to say, it is a view of that face of the linotype mold adjacent to which the bottom of the linotype is

made. Fig. 2 is a sectional view on line 2—2 of Fig. 1.

The mold A is essentially a block of metal having parallel front and rear faces, and a type slot a^1 extending through it from front to rear of the dimensions of the linotype to be cast. Usually this block is built up of several pieces, as, for example, the top and bottom pieces a' , a , the intermediate liners a^2 , a^3 , and the end bars a^4 , a^5 , as shown in the drawing; but these details of construction are immaterial to the present invention. 55

The mold is removably clamped in a suitable carrier, as, for example, frame B. If, as with the construction shown, the mold is to be moved in a straight path between the casting and ejecting positions, this frame 70 may be suitably held upon and supported by a movable rack bar C, to which power may be applied to move it in straight guideways back and forth. With this construction it is desirable to interpose between the 75 ends of the mold frame and the upturned ends of the rack bar the springs D, D. With this construction it is not necessary to carefully regulate the extent of movement of the mechanism which moves this rack bar. 80 The rack bar must be moved more or less beyond the position in which it would normally bring the mold to the correct casting position; but a stop of any suitable construction, as, for example, the stop K, may 85 be arranged opposite each end of the mold frame in position to be engaged thereby when the mold has reached the desired position,—whether the casting position or the ejection position. As the rack bar moves, a 90 little after the mold has reached either of these positions and has been stopped, one of the springs will be compressed and act thereafter to hold the mold form firmly 95 against said stop.

A plurality of holes are made through the top member a' of the mold. In each of these holes a vertically movable pin E is fitted. These pins extend into a recess b in the rear face of the upper member of the mold frame. 100 Each pin has an enlargement e in this recess and above the top member of the mold. A spring F associated with each of these pins is compressed between this enlargement and an overhanging part of the mold frame, 105 and therefore acts always to press the pin

downward. In each of these enlargements a recess is cut large enough to receive the longitudinally movable cam bar G which lies and is guided in its movements between 5 the back of the recess b in the mold frame and said pin. On each pin is an overhanging finger e', and in the top surface of the bar G adjacent to each pin is a recess g which is joined to the top surface of the bar 10 by a downwardly inclined surface g'. In the use of the mold, the described parts operate in the following manner. When the mold is moving toward the right as shown in Fig. 1, it is moving toward the casting 15 position. Just before it reaches the position the projecting end of bar G comes against any suitable sort of a stop whereby, since the bar is stopped and the mold continues its movement, the bar will be moved relatively to the mold so as to bring the recesses g beneath the overhanging fingers e' of the pins. The springs F will push the pins downward as far as the enlargements thereon will permit them to go, and this causes 20 the lower ends of the pins to project into the mold slot a sixteenth of an inch, more or less. The pins are in this position when molten metal is injected into the slot, and the linotype is cast. Then, when the mold 25 is moved in the contrary direction, during which movement the bottom of the linotype may be trimmed, as stated, the pins remain embedded in the linotype and therefore completely anchor it against any movement relative to the mold. Just before the mold reaches the ejecting position, the other projecting end of the bar G strikes a stop, as, for example, the stop K, and thereby the bar G is compelled to stop while the 30 mold goes on a short distance until it also is stopped. The relative movement of the bar G and the mold so produced causes the bar to move to the position shown in Fig. 1, and thereby the pins are lifted by the inclined surfaces g' and entirely withdrawn 35 from the mold slot so as to permit the linotype to be easily pushed out of the same.

Having described my invention, I claim:

1. The combination of a linotype mold 50 capable of moving from the casting to the ejecting position and vice versa, of a plurality of pins movable through the mold wall and adapted to be projected into the mold slot, a movable cam bar for controlling the simultaneous movement of all of said pins inward or outward as the case may be, and means which act automatically to move said cam bar in one direction when the mold 55

is near one end of its path and to move said cam bar in the other direction when the mold is near the other end of its path.

2. The combination of a linotype mold capable of movement from the casting to the ejecting position and vice versa, of a plurality of pins movable through the mold 60 wall and adapted to be projected into the mold slot, of a bar suitably supported adjacent to the mold and to said pins, and having cam surfaces for engagement with said pins, means for moving said bar first in one direction and then in the other, relative to said mold, and springs acting to hold the pins against the operative edge of said bar.

3. The combination of a linotype mold capable of movement from the casting to 75 the ejecting position and vice versa, of a plurality of pins movable through the mold wall and adapted to be projected into the mold slot, of a bar suitably supported adjacent to the mold and to said pins, and having 80 cam surfaces for engagement with said pins, said bar having projecting ends by which it may be pushed first in one direction and then in the other, and springs acting to hold said pins against the operative edge of said 85 bar.

4. The combination of a mold having a mold slot and a plurality of holes going through one side of the mold and connecting with said mold slot, a mold frame in which 90 said mold is removably held, pins fitted in said holes having enlargements above the mold, springs compressed between said enlargements and an overhanging part of the mold frame, and a longitudinally movable 95 bar having cam surfaces for engagement with overhanging fingers on said pins, said bars having their ends projected through and beyond the end members of the mold frame.

5. In a linotype mold, the combination of a mold, a mold frame in which the mold is removably held, a bar on which the mold frame is movably supported, and springs 100 interposed between the ends of the mold frame and the ends of said bar, said bar having means to which power may be applied to move it, and stops interposed in the path of the mold frame.

In testimony whereof, hereunto affix my 110 signature in the presence of two witnesses.

ARTHUR W. LE BOEUF.
